UNITED STATES PATENT OFFICE.

BERNARD BERGMANN, OF DETROIT, MICHIGAN.

TROUGH-FLUSHER.

1,202,653.

Specification of Letters Patent. Patented Oct. 24, 1916.

Application filed September 7, 1915. Serial No. 49,156.

To all whom it may concern:

Be it known that I, BERNARD BERGMANN, a citizen of the United States of America, residing at Detroit, in the county of Wayne 5 and State of Michigan, have invented certain new and useful Improvements in Trough-Flushers, of which the following is a specification, reference being had therein to the accompanying drawings.

10 In the operation of drains in floor of bars and counters, and in other places, that are set into floors and the like and are usually formed of tile or cementitious material, it is desirable to have a controllable water 15 supply from fittings that do not clog readily, that do not protrude above the surface and that are readily accessible for inspection and cleaning.

This invention relates to a flusher adapted 20 for use with floor drains or the like and to an arrangement thereof whereby a substantially continuous extension of a drain bed that does not clog and that is easily mounted in position is obtained.

25 The invention consists in the matters hereinafter set forth, and more particularly pointed out in the appended claims.

Referring to the drawings, Figure 1 is a 30 plan view of a flusher that embodies features of the invention; Fig. 2 is a transverse vertical section of the flusher in operative position within a bed or floor of cementitious material; Fig. 3 is a longitudinal vertical section through the same showing a portion 35 of a gutter or trough to which it is applied in use; Fig. 4 is a sectional detail taken on or about line IV—IV of Fig. 3.

In the drawings an upright inlet barrel 1 has a depending flared end portion 2 into 40 which a valve casing 3 is screwed or otherwise suitably fitted. The depending nipple 4 of the casing is adapted to receive a pipe or pipe coupling. An annular valve seat 5 in the casing 3 may be sealed by a closure 6 45 that is carried by a valve stem 7, the enlarged and screwthreaded portion 8 of which is in screwthreaded engagement with the casing, water passages 20 being provided in the casing at each side of the enlarged por-

tion of the stem, all as in the usual construction of valve members, the construction of the valve *per se* not being a part of this invention, as any type of valve that is operated by a rotatable stem may be used.

A floor plate of suitable contour having a 55 marginal flange 9, is preferably formed integral with the upper end portion of the barrel 1, and a suitable annular flange 10 on the floor plate is arranged concentric with an opening in the plate through which 60 the valve stem 7 passes, said flange being screwthreaded to receive a compression nut 11 which is adapted to compress a packing 12 within the flange around the stem and form a tight gland or stuffing box through 65 which the stem 7 projects. A hand wheel 13 or the like below the plane of the rim of the flange 9 provides means for manipulating the valve.

A transversely arranged upwardly projecting hollow boss 14 on the plate has an oblique discharge slot 15 in the front wall thereof that is in communication through a passage 16 in a downwardly extending hollow boss or connection 17 of the plate 70 with the interior of the barrel 1. The cross-sectional contour of the open end portion 75 of the floor plate corresponds with the cross sectional contour of the trough or gutter 22 formed in the cementitious or other material of the floor 18 or other part into which the plate is embedded and anchored by lugs 21 thereon. The direction of flow from the slot 15 is downward across the smoothly rounded surface 19 of the floor plate which 80 forms an end portion for the trough or gutter 22.

As a result of this construction a flusher 85 is obtained that forms a substantially continuous extension of the gutter, trough or 90 the like to which it is applied, and the flow from the discharge into said extension is in such a direction as to prevent lodgment of debris to clog it, while the valve operating parts are below the level of the floor and 95 there are no parts projecting above the plane of the upper edge of the trough to become injured and the trough is unobstructed.

Obviously changes in the details of construction may be made without departing from the spirit of the invention and I do not care to limit myself to any particular form or arrangement of parts.

What I claim is:—

1. A flusher comprising a plate having a cross-sectional form corresponding to the cross-sectional form of the open end of a trough to which it is adapted to be applied, said plate being provided with a discharge opening adapted to direct fluid into said trough over the bottom thereof, and means carried by the plate for supplying fluid to be discharged through the discharge opening.

2. The combination with a body of cementsitious material forming a trough having an open end, of a plate embedded in said body and forming a closed end for the open end of said trough conforming to the cross-sectional end portion thereof, said plate being formed with a fluid discharge opening arranged to direct water longitudinally and downwardly over the bottom of the trough, and means carried by said plate for supplying a fluid to said discharge opening.

3. A flusher comprising a plate adapted to be secured at one end of a trough as a continuation thereof and having a form corresponding thereto, said plate being provided with a fluid discharge opening arranged to discharge longitudinally and downwardly over the bottom of said plate and trough, means on the plate forming a fluid passage leading to said discharge opening, and a valve to control said passage.

4. A flusher comprising a concave floor plate having a cross section corresponding to a trough to which it is to be applied at an open end thereof and formed with a boss having a discharge slot in the side wall thereof, a depending barrel in communication with said slot, a valve in the barrel, and means for manipulating the valve extending through the floor plate and lying below the plane of the upper marginal portions thereof.

5. A flusher comprising a floor plate adapted to be secured at the open end of a floor trough to form a continuation thereof and having a marginal flange the upper edge of which is adapted to lie in the plane of the upper edge of the trough, said plate being formed with an upwardly projecting hollow boss at a distance from the end flange of the plate, said boss being formed with a discharge opening to direct fluid downwardly and along the bottom of the plate and trough, a member depending from the plate forming a fluid passage discharging through said opening in said boss; a valve in said member, and means for operating the valve extending through the plate between the end flange thereof and said boss

and lying below the plane of the upper edge 65 of the marginal flange of said plate.

6. The combination with a trough of cementsitious material, of a floor plate embedded therein and forming a substantially flush continuation thereof at one end, a barrel depending from the plate, a raised hollow portion of the plate having a transverse slot on the top side in communication with the interior of the barrel, a valve detachably secured on the lower portion of the barrel 70 for regulating the flow therethrough, and means for manipulating the valve extending through the floor plate and lying below the plane of the upper margin thereof.

7. A flusher comprising a floor plate 80 adapted to be secured at the end of a trough as a flush continuation thereof, a hollow boss transversely disposed on the plate and provided with a transverse downwardly directed slot in the wall toward the trough 85 end of the plate, a hollow barrel depending from the plate, a hollow boss whose interior forms a channel connecting the interior of the slotted boss with the barrel, a valve detachably secured on the lower end of the 90 barrel, and means for manipulating the valve that extends through the floor plate and lies below the plane of the upper margins thereof.

8. In a flusher, a floor plate having an 95 open trough end with cross sectional contour corresponding to the trough to which it is to be applied, a hollow boss formed in the surface of the plate transversely thereto with the upper face at least flush with or 100 below the level of the upper margin of the floor plate, a barrel depending from the rear portion of the plate, a hollow boss on the lower side of the plate forming communication between the slotted boss and the 105 barrel, the plate and the bosses and barrel being formed integrally, a valve casing detachably secured on the lower portion of the barrel, a closure controlling the flow through the casing, a rotatable member for operating the closure extending through the barrel and floor plate, a packing gland on the floor plate engaging around the rotary member, and a handle for turning the rotary member placed below the plane of the upper 115 margins of the floor plate.

9. A flusher comprising a smoothly concaved and flanged plate having an open end the cross section of which corresponds in contour to that of a trough to which the 120 plate is applied, a hollow boss extending transversely across the plate and having a transverse slot in the walls adjacent the trough end of the plate that is downwardly oblique, a barrel depending from the plate 125 behind the transverse boss, a boss on the lower face of the plate forming a communication between the interior of the barrel

and the interior of the slotted boss, a valve casing detachably secured on the lower end of the barrel, a closure for the casing, a rotatable member for manipulating the closure extending upwardly through the barrel, a packing gland on the plate aligned with the valve casing through which the rotary member extends, means for turning the rotary member lying below the margin of

the plate, and exterior anchoring lugs projecting from the plate.

In testimony whereof I affix my signature in presence of two witnesses.

BERNARD BERGMANN.
